CLAIM

The ornamental design for a bottle, as shown and described.

DESCRIPTION

FIG. 1 is a perspective view showing the bottle;
FIG. 2 is a front elevation view thereof, the rear elevational view being a mirror image thereof;
FIG. 3 is a left side view thereof, the right side elevational view being a mirror image thereof;
FIG. 4 is a top plan view thereof; and,
FIG. 5 is a bottom plan view thereof.

The broken lines shown in the Figures are included to show unclaimed subject matter only and form no part of the claimed design.
